UNITED STATES PATENT OFFICE

BEN F. DERRYBERRY, OF LEWISBURG, TENNESSEE

PENCIL SANDING MACHINE

Application filed March 27, 1930. Serial No. 439,371.

This invention relates to new and useful improvements in pencil sanding machines and has for its primary object to provide in a manner as hereinafter set forth, a machine of this character embodying a construction and arrangement of parts whereby the pencils will be successively sanded with great rapidity in a manner to prepare same for the subsequent painting operation.

Another important object of the invention is to provide a paper sanding machine which is adapted to operate on pencils of hexagonal cross section and which further embodies a construction whereby two diametrically opposite sides of the pencil will be sanded simultaneously.

Another important object of the invention is to provide, in a manner as hereinafter set forth, a pencil sanding machine of the character described which will sand the pencil longitudinally with the grain of the wood instead of crosswise to said grain as is done with sanding machines in use at present, thus preparing a more satisfactory surface for the reception of the paint.

Still another important object of the invention is to provide a pencil sanding machine embodying novel feeding mechanism which is positive and automatic in its action in feeding the pencils from a supply hopper to the sanding operation.

Other objects of the invention are to provide a pencil sanding machine of the character set forth which will be simple in construction, strong, durable, efficient in its use and which may be manufactured at low cost.

All of the foregoing and still further objects and advantages of the invention will become apparent from a study of the following description, taken in connection with the accompanying drawings wherein like characters of reference designate corresponding parts throughout the several views, and wherein:

Figure 1 is a view in side elevation of a pencil sanding machine constructed in accordance with this invention,

Figure 2 is a vertical cross sectional view taken through the hopper substantially on

the line 2-2 of Figure 1 looking in the direction indicated by the arrows.

Figure 3 is a detail view in cross section showing a pair of rollers which feed the pencils to the sanding mechanism,

Figure 4 is a detail view in side elevation of one of the pencil feeding rollers,

Figure 5 is a view illustrating the arrangement of the sanding belt and the pressure rollers which maintain said belt in engagement with the sides of the pencil,

Figure 6 is a cross sectional view showing the means for actuating the device which controls the passage of the pencils from the hopper,

Figure 7 is a detail view in elevation of the barrel through which the pencils pass when being sanded,

Figure 8 is a view taken substantially on the line 8-8 of Figure 7.

Figure 9 is a cross sectional view taken substantially on the line 9-9 of Figure 7.

Figure 10 is a cross sectional view taken substantially on the line 10-10 of Figure 7.

Figure 11 is a detail view in top plan showing the slideable follower which moves the pencils from beneath the hopper to the feed rollers.

Figure 12 is a cross sectional view taken substantially on the line 12-12 of Figure 1 looking in the direction indicated by the arrows, and illustrating the sanding mechanism,

Figure 13 is a fragmentary view in longitudinal section showing the entrance end of the barrel,

Figure 14 is a detail view in longitudinal section showing the pencil guide which is interposed between the feed rollers and the barrel,

Figure 15 is a detail view in cross section through the follower taken substantially on the line 15-15 of Figure 1,

Figure 16 is a cross sectional view taken substantially on the line 16-16 of Figure 1 looking in the direction indicated by the arrows,

Figure 17 is a view in vertical longitudinal section showing the pencil supply and feeding mechanism,

Figure 18 is a view showing the driving chain, belt and sprocket for actuating the various elements comprised by this invention.

5 Referring to the drawings in detail and to Figure 1 thereof in particular, it will be seen that reference numeral 1 designates generally a supporting stand comprising the pairs of vertically disposed front and rear legs 2 and 10 3 respectively upon the upper end of which is mounted a horizontally disposed rectangular frame which includes the longitudinal side bars 4 and 5.

15 Mounted on the rear end portion of the supporting frame between the side bars 4 and 5 is a base 6 provided with an integral rearwardly directed extension 7. A groove 8 is formed longitudinally in the upper side of the base 6 and the extension 7 for slidably 20 receiving the follower rod 9 which, as best seen in Figures 11 and 17, is mounted on one end portion of the cross head 10 of the bar 11 which in turn is mounted for reciprocatory movement longitudinally in the extension 7 25 on one side of the groove 8.

A guide rod 12 is mounted on the opposite end portion of the cross head 10 for sliding movement in the groove 13 formed in the extension 7. A coil spring 14 encircles the 30 follower rod 9 and has one end impinged against the free end of the extension 7 and its opposite end impinged against the cross head and in a manner normally urge said cross head and the rod rearwardly.

35 A hopper comprising a pair of complementary front and rear vertically disposed sections 15 and 16 is mounted on the base 6 and each of said sections 15 and 16 comprises a substantially V-shaped side walls 17 having 40 the integral downwardly converging marginal flanges 18 communicating with the channel 19 formed in the integral extension 20, said passages 19 communicating with the groove or channel 8 in the base 6.

45 A shaft 21 is mounted for rotation through the upper portions of the extension 20 on one side of the passages 19 and fixed on the opposite end portion of said shaft 21 between the hopper sections 15 and 16 is a pair of 50 cams 22 which are adapted to control the passage of the pencils through the passages 19. The shaft 21 projects forwardly from the hopper section 15 and has fixed thereon a drive pulley 23.

55 Spaced, opposed, longitudinally extending plates 24 are mounted on the base 6 adjacent the forward side of the hopper section 15 and mounted for rotation between said plates through the medium of the rotary shafts 25 60 which are journaled therethrough are the pairs of complementary feed rollers 26 and 27. As best seen in Figures 3 and 4 of the drawings, each of the feed rollers comprises a disk 28 upon the periphery of which is 65 mounted a rubber annulus 29 having a poly-

onal circumferentially extending channel 30 in its periphery.

The annuli 29 are formed of soft rubber. The feed rollers of each pair are spaced slightly apart and are positioned to receive therebetween the pencils from the channel 9 as said pencils pass through the throat 31 in the lower end of the hopper section 15. The shafts 25 have fixed on one end the meshed gears 32 which are operatively connected to 75 a drive gear 33 fixed on one end of a shaft 34 having a worm 35 fixed on its opposite end portion.

Longitudinal strips 36 are mounted on the upper edges of the plates 24 in any suitable 80 manner and mounted on said strip in longitudinally spaced relation of the blocks 37 which support a pair of transversely extending bars 38 therebetween. A brush 39 is secured between intermediate portions of the 85 bars 38 and depends therefrom for engagement with the uppermost of the pairs of feed rollers 26 and 27 in a manner to keep said feed rollers clean.

As best illustrated in Figures 1 and 14, a 90 guide 40 is mounted on the forward end portion of the base 6 and said guide comprises a pair of upstanding arms 41 and 42, the latter having a rearwardly extending integral neck 43 terminating in a head 44. The arms 41 95 and 42, the neck 43 and the head 44 are provided with aligned hexagonal bores 45 the rear end portions of which are flared. The guide 40 is adapted to receive the pencils from the feed rollers 26.

100 Mounted on the longitudinal beams or bars 4 and 5 of the supporting frame at a point forwardly of the guide 40 (see Figures 1 and 12) is a substantially inverted U-shaped bracket 46 having the depending arm portion 105 47 and 48 which rests on top of the longitudinal bars 4 and 5 respectively and a cross beam 49 is formed integrally with the depending arm portions 47 and 48 and extends therebetween adjacent the bars 4 and 5.

110 Standards 50 are rigidly mounted on the bars 4 and 5 in forwardly spaced relation to the bracket 46. It should be here mentioned that the standards 50 are in staggered relation with respect to each other on the bars 4 and 5. An arm 51 extends upwardly from the standard 50 on the bar 4 and a shaft 52 is mounted between said arm 51 and the bracket 46 for rotation and has fixed thereon a pulley 53.

115 The shaft 52 extends forwardly through the bracket 46 and has fixed thereon a sprocket 54. Depending from the bar 5 of the supporting frame is a pair of curved arms 55 between the free ends of which is mounted for 125 rotation a pulley 56. Brackets 57 are mounted on the bars 4 and 5 in staggered relation with respect to each other and opposite to the standard 50 and beams (not shown) identical in construction to the beams 49 of the 130

brackets 46 extend between said standards 50 and the brackets 57.

An arm 58 extends upwardly from the forward end portion of the bar 5 of the supporting frame and a shaft 59 extends between said arms and the brackets 46 for rotation and has fixed on its forward end portion a large sprocket gear 60 and a comparatively small sprocket gear 61.

10 A pulley 62 is fixed on the forward end portion of the shaft 59 adjacent the arm 58. A pair of depending arms 63 extend downwardly and inwardly from the bar 4 of the supporting frame and rotatably mounted 15 therebetween is the pulley 64.

A beam (not shown) similar to the beam 49 also extends from the lower end portion of the arm 58 for rest on the beam 4. Pulleys 65 and 66 are mounted for rotation on the 20 bars 4 and 5 respectively. The beam 49 and all of the transverse beams which are similar thereto is provided with an intermediate circular enlargement 67 provided with a rectangular opening through which extends the 25 elongated barrel 68 having a hexagonal bore 69 extending longitudinally therethrough.

The entrance end of the bore 69 is flared as indicated at 70 (see Figure 13) and in horizontal alinement with the bores 45 in guide 30 40. As clearly illustrated in Figures 7 to 10 inclusive of the drawings, the sides of the barrel 68 are provided with longitudinally extending recesses which communicate with diametrically opposite sides of the bore 69 at 35 different points in the barrel and in a manner to successively expose the opposite sides of the pencil 71 which is passing therethrough.

Endless sanding belts 72 are trained over the pulleys 53 and 56, the pulleys 62 and 64 40 and the pulleys 65 and 66.

Both flights of each of the endless standing belts are maintained in engagement with the exposed sides of the pencils which are passing through the barrel 68 through the 45 medium of the rollers 73 which, if desired, may be spring pressed.

A pan 74 is mounted on the forward end of the supporting frame 1 to receive the standard pencil from the discharge end of the barrel 68. Suction pipes 69 are associated with the standing belts 72 to convey dust therefrom.

An electric motor 76 is mounted on a support 77 secured to the leg 2 of the frame 1 and 55 said motor drives an endless belt 78 trained over a large pulley wheel 79 supported for rotation in the arm 80 which projects forwardly from the leg 3 of the supporting frame 1. The pulley 79 drives a shaft 81 which extends 60 transversely beneath and has fixed thereon a pulley 82 over which extends an endless belt 83 which drives a pulley 84 fixed on a shaft 85 mounted for rotation in the bracket 86 which depends from the rear end of the 65 base 6.

A disk 87 is fixed on the shaft 85 for rotation therewith and has eccentrically secured thereto a connecting rod 88 which is operatively connected to the cross head 10 for reciprocating the follower rod 9.

Also fixed on the shaft 81 is a sprocket 89 over which is trained a sprocket chain 90 which is operatively connected to the shaft 91 in a manner to rotate same. The shaft 91 drives the pulley 23 and the shaft 21 of the feed regulator through the medium of the pulley 92 and the belt 93. The shaft 91 is also operatively connected to the stub shaft 94 mounted in the depending arm 95 through the medium of the sprocket chain 96 and the shaft 94 drives the large gear 60 through the medium of the sprocket chain 97.

A tightener 98 is provided for operative engagement with the chain 97. An endless chain 99 is operatively connected to the shafts 85 upon which the pulleys 53, 62 and 66 are fixed, said chain 99 deriving its power from the sprocket 61 on the shaft 59 upon which the large gear 60 is mounted and in this manner each of the standing belts 72 is actuated.

In use, the pencils from the hopper are fed one at a time in rapid succession into the channel 8 and the follower rod 9 pushes each pencil between the pairs of rollers 26 and 27 which in turn feed same through the guide 40 into the barrel 68. Each succeeding pencil pushes the preceding pencil through the barrel.

The endless sanding belt moves very slowly owing to the reduction gearing by which same are driven but the pencils travel through the barrel at great speed with the result that sanding operation is longitudinal with the grain of the wood of said pencil and not transversely thereto.

As will be readily apparent, each of the belts 72 is adapted to sand two sides of the pencil simultaneously as said pencil passes through the barrel.

It is believed that the many advantages of a pencil sanding machine constructed in accordance with this invention will be readily understood, and although the preferred embodiment of the invention is as illustrated and described, it is to be understood that changes in the details of construction may be had which will fall within the scope of the invention as claimed.

Having thus described the invention what I claim as new is:

1. A pencil sanding machine of the character described comprising, in combination, a supporting stand, an elongated barrel mounted on the stand having a bore therein for the passage of the pencils, said barrel being provided, at longitudinally spaced points, with pairs of elongated, diametrically opposite openings communicating with the bore in a manner to successively expose different portions of the sides of the pencil as said pencil

passes through the barrel, means for driving the pencil through the barrel, pairs of supporting members on the stand, shafts mounted between the pairs of supporting members 5 and disposed in pairs in transverse alignment with the pairs of openings in the barrel, a sprocket gear fixed on one end portion of one shaft of each pair, an endless chain trained over the sprocket gears, another sprocket gear fixed on one of said one shafts, a chain trained over the last named sprocket gear for connecting same to a source of power, a pair of pulleys operatively mounted on the shafts, and endless sanding belts trained over the 10 pairs of pulleys and operatively engageable with the exposed portions of the pencil in the barrel.

2. A pencil sanding machine of the character described comprising a supporting stand, 20 an elongated barrel mounted on the stand having a bore therein for the passage of the pencils, sanding belts engageable with the pencils in the barrel, means for driving the belts, a supply hopper mounted on the stand, feeding 25 means mounted on the stand and spaced from the barrel for receiving the pencils from the hopper and driving said pencils through the barrel, means for driving the feeding means, and a guide disposed between the 30 feeding means and the barrel, said guide including a pair of spaced, opposed, upstanding arms and a connecting base portion, a neck projecting laterally from one of the arms, said neck and the arms being provided 35 with aligned bores for the passage of the pencils, said bores being aligned with the bore of the barrel and having their intake end portion flared for guiding the pencils thereinto.

40 3. A pencil sanding machine of the character described comprising a supporting stand, a barrel mounted on the stand having a bore therein for the passage of the pencils, sanding belts mounted on the stand for operative 45 engagement with the pencils in the barrel, means for actuating the sanding belts, and means for feeding pencils to the barrel, the last named means including a base mounted on the stand, an extension formed integrally 50 on the base, said base and the extension having a pair of parallel, longitudinal grooves in their upper side, a bar slidable on the base and the extension between the grooves and projecting from the free end of the extension, a cross head on the outer end of the bar, a hopper, for the reception of the pencils, mounted on the base above one of the grooves for depositing the pencils therein, pairs of 55 opposed feed rollers disposed between the hopper and the barrel, a follower fixed on one end portion of the cross head and slidable in said one groove for moving the pencils toward the feed rollers, a guide rod fixed on the 60 other end portion of the cross head and slid- 65

able in the other groove, means for reciprocating the cross head and means for actuating the feed rollers.

In testimony whereof I affix my signature.
